UNITED STATES PATENT OFFICE

GEORGE E. NERNEY, OF ATTLEBORO, MASSACHUSETTS, ASSIGNOR TO BAY STATE
OPTICAL COMPANY, A CORPORATION OF MAINE

EYEGLASS CONSTRUCTION

Application filed February 12, 1929. Serial No. 339,343.

This invention relates to eyeglass construction and more particularly to the construction of eyeglasses held in position by swinging levers or the like.

One of the objects thereof is to provide a simple and practical construction of the above nature characterized by a high degree of strength and rigidity in use. Another object is to provide a construction of the above nature which shall be compact and self-contained and of attractive appearance. Another object is to provide a construction of the above nature in which the parts are arranged for efficient and dependable action and the lenses firmly held in an advantageous position. Other objects will be in part obvious and in part pointed out hereinafter.

The invention accordingly consists in the features of construction, combinations of elements, and arrangements of parts as will be exemplified in the structure to be herein-after described and the scope of the application of which will be indicated in the following claims.

In the accompanying drawing, in which is shown one or more of various possible embodiments of the several features of this invention,

Figure 1 is a front elevation partially in section along the line 1—1 of Fig. 2;

Fig. 2 is a plan partially in section along the line 2—2 of Fig. 1;

Fig. 3 is a detail elevation of a portion of a lever in part broken away to show the construction more clearly; and

Fig. 4 is a sectional elevation of a portion of another embodiment of certain features.

Similar reference characters refer to similar parts throughout the several views of the drawing.

Referring now to Fig. 1 of the drawing, there are shown a pair of lenses 10 resting within rims 11. Interposed between these rims is a bridge 12; and as the construction at each side of the eyeglass frame is substantially identical, that on one side only will be described in detail.

The bridge 12 comprises a portion 13 leading to the rim or lens support 11. It may here be noted that the term "lens support"

is used throughout in a broad sense to denote any form of device for supporting a lens in position, although the specific form here shown is that of a rim encircling the lens. It may also be noted that the term "eyeglasses" is broadly used to comprehend not only devices of this sort supported from the nose only, but those of the so-called spectacle type having supports at the outer ends of the lenses.

Extending downwardly and thence outwardly from the bridge is a part 14 connected at 15 to the rim. In a sense, this may be considered as a portion of the bridge.

Rigidly connected with the rim and extending laterally therefrom is a projection or lug 16 which is preferably connected at its outer end with the part 14. This lug 16 has formed thereon a bearing surface 17 preferably beveled or inclined upwardly and inwardly as shown.

Likewise extending laterally from the lens support at a position upwardly spaced from the lug 16 is a lug 18 having a bearing surface 19 substantially registering with the bearing surface 17 and also preferably inclined upwardly and inwardly.

Passing between the parts 16 and 18 is a lever 20 provided at its rear end with any desired form of nose-engaging member 21, and at its forward end with the usual finger-grip 22. At a portion of this lever embraced by the lugs 16 and 18 there is formed a hollow cylindrical portion 23 having thereon bearing surfaces 24 and 25 respectively fitting and coacting with the bearing surfaces 17 and 19. It is understood that the beveled or inclined arrangement of these surfaces is slight so that the lever can be snapped in and out of position between the lugs 16 and 18.

Coiled within the barrel 23 is a spring 26, the lower end of which rests within a slot 27 formed in the lever. The upper end of the spring passes through an axially elongated slot 28 and coacts with the rim or other stationary part of the frame as shown at 29. This spring is so wound and tensioned as to tend to swing the nose-engaging member 21 in an inward direction or di-

rection toward the nose, the movement being permitted by the slot 28 and limited as by the stop surface 30.

5 A screw 31 passes downwardly through the lug 18 and is threaded into the lug 16, tending to add to the security of assembly of the parts and, if desired, to serve to vary the pressure upon the bearing surfaces.

10 As best shown in Fig. 2 of the drawing, the portion 13 of the bridge is preferably rearwardly curved to permit ready access to the screw 31.

15 By the arrangement shown, the lens is firmly held in position and the swinging lever given a solid support. Furthermore, the parts are so compactly disposed as to permit the use of large lenses without undue increase of the pupillary distance. The bridge construction is not only advantageous 20 in the above respect but tends to enclose and shield the pivotal joint of the lever, and the latter in turn encases and protects the spring and bearing surfaces at the joint. There are no unsightly crevices 25 tending to collect dirt and perspiration, and yet the parts may be assembled and taken apart with ease.

30 In the construction shown in Fig. 4 of the drawing, the lens 32 is held within a rim 33, the ends of which abut against each other at 34. The lug 35 is formed upon one end of the rim and the bridge 36 is provided with an enlargement 37 secured to the opposite end of the rim. Between these parts 35 and 37 is fitted a lever 38 provided with a spring 39 the construction and action of which will be clear from the description of the embodiment shown in Fig. 1 of the drawing. Passing upwardly through the 40 lug 35 and threaded into the part 37 is a screw 40 which serves not only to aid in the security of attachment of the lever, but connects the two ends of the rim one to another.

45 Certain of the advantageous features of the construction shown in Fig. 1 are inherent in that illustrated in Fig. 4 of the drawing.

50 It will thus be seen that there is provided a compact and practical eyeglass frame or mounting in which the several objects of this invention are achieved.

55 As many possible embodiments may be made of the above invention and as many changes might be made in the embodiments above set forth, it is to be understood that all matter hereinbefore set forth or shown in the accompanying drawing is to be interpreted as illustrative and not in a limiting sense.

60 I claim:

65 1. In eyeglass construction, in combination, lens-supporting means, a part extending from said lens-supporting means, a lever mounted upon said part, a screw extend-

ing through said lever into said part, and a bridge connected to said lens-supporting means and having a portion rearwardly offset about the head of the screw to allow access to said screw in a vertical direction. 70

2. In eyeglass construction, in combination, lens-supporting means, a part extending from said lens-supporting means, a lever mounted upon the upper surface of said part, a screw extending downwardly through said lever and threaded into said part, said lever comprising a hollow pivotal portion, a spring mounted within said hollow pivotal portion and tending to swing said lever, and a bridge connected with said lens-supporting means above said lever and having a portion rearwardly offset to permit access downwardly to said screw. 75 80

3. In eyeglass construction, in combination, lens-supporting means, a bridge extending to said lens-supporting means, a member extending from said bridge to said lens-supporting means at a point spaced from its connection with said bridge, a member extending from said lens-supporting means at a point above said first member, and a swinging lever pivotally mounted between said two members. 85 90

4. In eyeglass construction, in combination, lens-supporting means, a bridge extending to said lens-supporting means, a member extending downwardly and inwardly from a point on said bridge to said lens-supporting means and secured thereto at a point spaced from its connection with said bridge, a lever mounted upon said member, and a screw extending through said lever into said member, said bridge having a portion rearwardly offset about the head of said screw to allow access to said screw in a downward direction. 95 100 105

5. In eyeglass construction, in combination, lens-supporting means, a bridge connected to said lens-supporting means, a pair of parts projecting from said lens-supporting means, a swinging lever pivotally mounted between said parts, and a screw passing through one of said parts and said lever and into the other of said parts, said bridge having a portion rearwardly offset about the head of the screw shaped to allow access to said screw in a downward direction. 110 115

6. In eyeglass construction, in combination, lens-supporting means, a bridge extending to and secured to said lens-supporting means, a member extending downwardly and inwardly from a point on said bridge to said lens-supporting means and secured thereto at a point spaced from its connection with said bridge, a lever passing between said bridge and said member and provided with a hollow pivotal portion and pivotally connected to said member independently of the bridge, and a spring enclosed within and con- 120 125 130

nected to said hollow portion and adapted to swing said lever.

7. In eyeglass construction, in combination, a lens-supporting member, a bridge extending to and connected to said lens-supporting member, a member extending downwardly and inwardly from a point on said bridge to said lens-supporting member at a point spaced from the point of connection of said bridge and said lens-supporting member, a second member extending from said lens-supporting member below said bridge and above the bottom portion of said first mentioned member, a lever having a barrel connected thereto, said barrel lying between said first member and said second member, a spring enclosed within said barrel and adapted to swing said lever toward the nose of the wearer, and a screw passing through said second member and said barrel and threaded into said first member.

8. In eyeglass construction, in combination, a lens-supporting member; a bridge having an arched central portion, thence extending downwardly in a gradual curve and upwardly, connected to said lens-retaining member; a member secured to said bridge at substantially said downwardly extending portion thereof, extending downwardly substantially at right angles to said bridge, thence inwardly toward said lens-retaining member at a point spaced from and below the point at which said bridge is connected to said lens-retaining member; and a swinging lever mounted between said bridge and said member and having secured thereto a nose engaging member.

9. In eyeglass construction, in combination, lens-supporting means, a bridge connected to said lens-supporting means, a member extending downwardly and inwardly from a point on said bridge to said lens-supporting means and secured thereto at a point spaced from its connection with said bridge, a lever passing between said bridge and said member, a member extending through said lever, and means rigidly supporting said lever upon each side thereof independently of the bridge.

10. In eyeglass construction, in combination, lens-supporting means, a bridge connected to said lens-supporting means, a member extending downwardly and inwardly from a point on said bridge to said lens-supporting means and secured thereto at a point spaced from its connection with said bridge, a lever passing between said bridge and said member and provided with a hollow pivotal portion, a spring enclosed within and connected to said hollow portion and adapted to swing said lever, a member extending through said lever, and means rigidly supporting said lever upon each side thereof independently of the bridge.

11. In eyeglass construction, in combina-

tion, lens-supporting means, a bridge extending to said lens-supporting means, a member extending downwardly from a point on said bridge to said lens-supporting means at a point spaced from its connection with said bridge, a lever passing between said bridge and said member and provided with a hollow pivotal portion, a spring enclosed within said hollow portion and connected thereto to swing said lever, a member passing through said lever, and means rigidly supporting said lever independently of the bridge, said bridge having a rearwardly offset portion about the head of said last-mentioned member to allow access thereto.

In testimony whereof, I have signed my name to this specification this 25th day of October, 1928.

GEORGE E. NERNEY.
